United States Patent Office.

ALEXANDER N. REDMAN, OF CHARLESTOWN, MASSACHUSETTS.

Letters Patent No. 64,033, dated April 23, 1867.

IMPROVED FILE-CUTTING MACHINE.

The Schedule referred to in these Letters Patent and making part of the same.

Be it known that I, ALEXANDER N. REDMAN, of Charlestown, in the county of Middlesex, and State of Massachusetts, have invented certain new and useful Improvements in Machines for Cutting Files, of which the following is a full, clear, and exact description, reference being had to the accompanying drawings, making part of this specification, in which—

Figure 1 is a plan view of the travelling platform and file-blank holder, with the cutting apparatus and frame removed.

Figure 2 is a side elevation.

Figure 3 is a vertical section; and

Figure 4 is a modification of the construction of the hammer or cutter-head.

Similar letters indicate like parts in the several figures.

The object of my invention is to produce a machine which will throw out the cuts on the file-blank, so as to form the teeth in the manner heretofore best accomplished by hand-work, and also to present the file-blank to the action of the cutter so that by a simple movement of the guide-frame and file-blank holder any desired angle of cut may readily be obtained; and the invention consists in so constructing and arranging the hammer or cutter-holder as to allow of an inward motion at the completion of the downward motion in such a manner as to throw out the surface cut; it also consists in operating the feed of the file-blank holder by means of a large gear-wheel, in combination with a small gear-wheel attached to a feeding-screw which actuates the file-blank holder, the large gear-wheel receiving an intermittent motion from a sliding-bar provided with a pawl and operated by a cam on the main shaft. The invention consists, also, in a method of adjusting the cutter in the cutter-head and arranging it so that it can be readily removed for sharpening or for repairs.

Referring to the drawings, A A' represent the base or supporting bed of the machine. A part of the base, A', is circular, and is raised above the part A. Around the circular part A' is fitted, so as to move easily, a gear-wheel, B. To the circular portion A of the base is attached a guide-frame, D, in such a manner that its direction may be changed across the base in order to admit of the file being presented to the cutter at different angles, a projection, a, on the under side securing it centrally on the base. In the guide-frame D is fitted, so as to slide freely, the file-blank holder E, in which the file-blank F is firmly set. At one end of the guide-frame D is a small gear-wheel or pinion, C, which meshes with the large gear-wheel B. The small gear is secured to one end of a large set-screw, G, which passes within the guide-frame D and works within a female screw formed in a head in the file-blank holder E, so that as the screw G is turned the file-blank holder will be gradually moved in the required direction. Motion is imparted to the large gear-wheel as follows: At one side of the base or bed A is a sliding-bar, H, moving in suitable guides. At a proper point above the portion of the gear-wheel B which passes under the slide H, is a pawl, I, so arranged as to catch in the teeth of the wheel B and move it in one direction; and as the sliding-bar H is moved backwards the pawl I will move over the teeth until brought to a point for the next forward motion. The forward motion of the bar H is effected by means of a three-armed cam, k, which arms, in their rotation, strike against a shoulder or raised portion, l, on the slide D. When the cam has passed over said shoulder or projection, the slide H is retracted by means of a spring attached to its rear end or by any other equivalent device. The projection k may be adjusted to vary the throw of the slide H, and thus regulate the distance between the cuts on the file-blank. Over the base or bed A A' is placed a suitable frame, M, for carrying the cutter-head and its attachments. M represents a block or head, having grooved sides, and fitted to slide on guides in the end of the upper frame in a direction to bring the cutter at an angle with the file-blank. N is a block secured in the upper part of the cutter-head, and is made adjustable in position so that it can be moved downwards and secured in position at any point as the cutter is worn away at its edge and becomes shorter. Below the adjustable block N is arranged the cutter O, which is held in position by means of a spring-yoke, P, provided at its lower ends with projections that take into corresponding notches in the upper part of the cutter on each side. The upper part of the yoke bears against the adjustable block N, and moves with the same. By opening the jaws or sides of the yoke P the cutter O will be released and can readily be removed for sharpening. As the edge wears away the block N is moved downward, bringing down the yoke so that the edge of the cutter will always maintain a proper relation to the file-blank. The cutter is arranged in the lower part of the head so as to have an independent motion at its lower part in a direction at right angles with its width. The lower part of the cutter is held against the

front portion of the cutter-head by means of a spring, or its equivalent, in which position it is retained when the cutter is not in contact with the file-blank; but when the cutter is brought down upon the said blank its angular position will cause it to throw out the surface cut in a manner similar to that effected by hand-work, which cannot be done by cutters that are rigidly fixed in the heads. The hammer or cutter-head is operated by means of a cam, L, striking against a block, l, and the length of the stroke of the said cutter-head may be regulated by adjusting the block l higher or lower in the head. The downward blow of the cutter is effected by means of a spring, S, arranged in the upper part of the frame, and passing under a pin or cross-bar in the centre, rests at its front end in a cross-piece, when the cutter-head has completed its downward stroke. A similar spring, S', is arranged in like manner in the lower part of the frame for the purpose of raising the cutter from the file-blank immediately after the blow is struck. The power of each spring may be regulated by a screw, T, at the rear, or by changing the position of the bearing-rods in front. Fig. 4 shows a modification of the device for adjusting the cutter, consisting of a screw which operates the adjusting-block N.

The operation is as follows: Motion being imparted to the shafts by any proper means, the cams k impart a reciprocating motion to the sliding-bar H in the manner above described, which in turn causes the gear-wheel to rotate intermittently. The rotation of the said wheel turns the pinion C, attached to the screw G, which latter causes the file-blank holder to move forward after each blow of the cutter upon the blank, the degree of motion being graduated by means of the adjustable projection h. The main shaft at the same time carries the cam L, which raises the cutter-head, the latter being brought down with force by means of the upper spring S, and retracted or raised from the file-blank by means of the lower spring S'.

Having thus described my invention, what I claim as new, and desire to secure by Letters Patent, is—

1. The combination of the guide-frame D, the pinion C, and rotating rack-gear B, as described.
2. I claim the sliding-block or bar H, provided with the pawl i, the adjustable projection h, and retracting spring I, in combination with the rotating rack-gear B, substantially as and for the purpose specified.
3. I claim the combination of the yoke P, adjustable block N, or its equivalent, and the cutter O, operating as described, substantially as and for the purpose set forth.
4. I claim the combination of the springs S S' arranged as described, with the cutter-head M, as and for the purpose specified.

In testimony whereof I have signed my name to this specification in the presence of two subscribing witnesses.
